UNITED STATES PATENT OFFICE.

DAVID RUSSELL GREENE, OF CHICAGO, ILLINOIS, ASSIGNOR OF ONE-THIRD TO GEORGE A. BAKER, JR., OF CHICAGO, ILLINOIS.

MUSIC-ROLL FOR PIANOLAS.

No. 863,167.

Specification of Letters Patent.

Patented Aug. 13, 1907.

Application filed May 2, 1906. Serial No. 314,748.

To all whom it may concern:

Be it known that I, DAVID RUSSELL GREENE, a citizen of the United States of America, and a resident of Chicago, Cook county, Illinois, have invented a certain 5 new and useful Improvement in Music-Rolls for Pianolas, of which the following is a specification.

My invention relates to music rolls for pianolas, or other similar piano or organ players. With rolls of this character more or less trouble has been experienced, owing to the uneven expansion and contraction 10 of the wood of the roll and the paper of the music wound thereon. These rolls are usually provided with end flanges, and the perforated sheet of paper constituting the music is wound upon the roll between these flanges. 15 With such arrangement, it is some times found that the paper expands and bears so hard on the said flanges that it does not unwind properly. Again, too much space will perhaps show its presence between the flanges and the ends of the roll of paper, thus interfering 20 with the proper winding and unwinding of the music.

Generally stated, the object of my invention is the provision of an improved construction for permitting the adjustment of the roll in accordance with the expansion and contraction of the paper and wood—that 25 is to say, the provision of improved means by which the flanges of the roll can always be adjusted in the same manner as to preserve the proper relation between these flanges and the ends of the paper roll, thus making it possible to move the flanges either toward or away 30 from the paper roll, as conditions may require.

Special objects of my invention are the provision of an improved flange-adjusting arrangement, whereby the flanges can be adjusted readily by hand, without the use of tools and without inserting or removing any 35 parts or devices; and the provision of certain details and features of improvement and combinations tending to increase the general efficiency and serviceability of an adjustable music roll of this particular character.

To the foregoing and other useful ends my invention 40 consists in matters hereinafter set forth and claimed.

In the accompanying drawings—Figure 1 is an enlarged side elevation of a music roll embodying the principles of my invention, the same being broken away at the middle for the convenience of illustration, 45 and one end being shown in longitudinal section. Fig. 2 is an end elevation of the said roll. Fig. 3 is a cross section on line 3—3 in Fig. 1.

As thus illustrated, my improved music roll comprises the cylinder or roll of wood A, which is provided 50 with reduced end portions a. The spindles B and B¹ are preferably of metal and are inserted in the ends of the roll, as shown. A threaded sleeve C is fitted upon each reduced end portion a of the roll. Upon these sleeves are screwed the adjustable metal flanges D. 55 These flanges are, of course, of greater diameter than

the cylinder of wood A, so as to expose more or less of their inner faces. Each flange has its inner face provided with sockets d arranged on the line of the circle, and each socket being preferably rounded, as shown. The roll or cylinder of wood A is provided with short 60 tubes a¹ inserted in the ends thereof, and arranged in line with the sockets d. Each tube contains a catch or locking device E and a spring e, the latter tending to keep the former pressed tightly against the inner face of the adjacent flange D. With this arrangement, the 65 spring-pressed pins or locking devices E engage the sockets d with sufficient pressure to prevent the winding and unwinding of the music F from rotating the flanges D. In other words, the flanges will remain at any desired position where they may be adjusted by 70 rotating them upon the screw-threaded sleeves C. At the same time, however, these flanges can be grasped and rotated in order to bring them to the desired positions, the tendency of the springs e being insufficient to resist the rotation thus given the flanges. For this 75 purpose, the ends of the pins or locking devices E are rounded, as shown. In this way, as stated, the winding and unwinding of the music will not disturb the flanges, but, at the same time, either flange can be grasped and rotated for the purpose of changing its 80 position relatively to the end of the roll of paper. Consequently, the flanges can always be quickly adjusted relatively to the roll of paper when the latter shrinks or contracts. This, of course, will tend to guard against tearing of the paper, and will insure accuracy in playing after the roll is inserted in the player. 85

What I claim as my invention is:—

1. In a music roll of the character specified, the combination of a cylinder, rotatable flanges for the ends of said cylinder, spring-pressed pins for engaging said flanges 90 and yieldingly holding the same in any desired position, and perforated music wound upon the cylinder between said flanges.
2. In a music roll of the character specified, the combination of the cylinder A, the threaded sleeve C secured to the ends thereof, screw-threaded flanges D screwed upon said sleeves, each flange provided with sockets d, the spring-pressed pins E adapted to engage said sockets on the flanges, and the perforated music F wound upon the cylinder between the flanges, substantially as set forth. 100
3. In a music roll of the character specified, the combination of a cylinder of wood provided with reduced end portions, sleeves, screw-threaded flanges secured upon said sleeves, said flanges being of greater diameter than said cylinder of wood, and means between the two flanges for 105 holding either flange in any desired position relatively to the ends of the cylinder.
4. In a music roll of the character specified, the combination of a cylinder provided with threaded end portions, flanges screwed upon said threaded end portions, and 110 spring-pressed members adapted to engage the inner faces of said flanges to hold the same in any desired relation to the ends of the cylinder.
5. In a music roll of the character specified, the combination of a cylinder provided with threaded end portions, 115

threaded flanges screwed upon said end portions, said flanges being adapted to be screwed toward and away from each other, each flange provided with a circular series of sockets, spring-pressed means for engaging said sockets to hold the flanges in any desired position, and perforated music wound upon said cylinder between said flanges.

6. In a music roll of the character specified, the combination of a cylinder, rotatable flanges for the ends of

said cylinder, and spring means for yieldingly holding 10 same in any desired position.

Signed by me at Chicago, Illinois, this 16th day of April, 1906.

DAVID RUSSELL GREENE.
